Primary Examiner — Susan Bennett Hattan*Assistant Examiner* — Janice Hallmark(57) **CLAIM**

The ornamental design for a mini vaporizer, as shown and described.

DESCRIPTION

FIG. 1 is a perspective view of a mini vaporizer;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a front view thereof, showing the plane upon which a cross-sectional view is taken and shown in FIG. 9; and, FIG. 9 is a side cross-sectional view thereof taken along line 9-9 of FIG. 8.

The broken lines in the drawings illustrate portions of the mini vaporizer which form no part of the claimed design.
